UNITED STATES PATENT OFFICE

PETER MARCHESINI, OF PEABODY, MASSACHUSETTS

ABRADING MACHINE

Application filed September 17, 1928. Serial No. 306,400.

The invention relates to machines for working upon sheet material by means of a roll of sand-paper, emery cloth or the like, and it aims to provide a machine of this character which is of simple and inexpensive nature, yet will be highly efficient and desirable.

With the foregoing in view, the invention resides in the novel subject matter herein-after described and claimed, description being accomplished by reference to the accompanying drawings.

Fig. 1 is a side elevation.

Fig. 2 is a vertical transverse section on line 2—2 of Fig. 1.

Fig. 3 is a longitudinal sectional view on line 3—3 of Fig. 2.

Fig. 4 is a horizontal sectional view on line 4—4 of Fig. 3.

The construction selected for illustration will be rather specifically described, with the understanding that within the scope of the invention as claimed, variations may be made.

The numerals 5 denote two parallel upper side plates having outstanding flanges 6 at their lower edges adapted to be bolted or otherwise secured to a floor or analogous support. Mounted in appropriate bearings 8 carried by the upper edges of the plates 5, 25 is a shaft 9 which is provided with a work-performing roll 10. This shaft may be driven in any desired manner, a tight pulley 11, a loose pulley 12, a belt 13, and a belt shifter 14 being shown for this purpose.

Extending between the plates 5 immediately under the roll 10, is a work-supporting table 15 which although slightly inclined is about horizontal as shown in Fig. 3. Screws 16 pass through vertical slots 17 in the plates 5 and are threaded into the table 15 to support the latter and to permit vertical adjustment thereof according to the thickness of the material to be sand-papered or otherwise acted upon.

Under the roll 10, table 15 is formed with a slot 18 extending longitudinally of said roll, and this slot receives the upper portion of a pressing roll 19. This roll 19 is provided with trunnions 20 which pass through vertically elongated openings 21 in the side plates

5 and are rotatably mounted in bearings 22 at the outer sides of said plates. These bearings are bolted or otherwise securely mounted upon longitudinal arms 23 whose rear ends are pivoted to the plates 5 as indicated at 24, 55 permitting vertical movement of said arms and corresponding movement of the parts 22—20—19, so as to cause the latter to press the work against the roll 10 with any desired degree of pressure. Appropriate spring devices 25 are connected with the arms 23 to normally swing them downwardly, the lower ends of these spring devices being preferably anchored to the flanges 6.

For upwardly swinging the arms 23, two longitudinal levers 27 are provided. These levers are fulcrumed between their ends at 28 to the plates 5 and the rear ends of said levers underlie the front ends of said arms. The front ends of the levers 27 are connected 70 by a transverse bar 29 which may be pinned rather loosely to the levers as indicated at 30. If desired, the front ends of these levers may be provided with depressed seats 31 receiving the bar ends as shown. Connected with and extending downwardly from the center of the bar 29, is an elastic operating connection which may be formed of a rod 32 and a spring 33. The lower end of this connection 32 is connected with a foot pedal 34 which may be pivoted at 35 upon a transverse rod 36 which extends between the lower portions of the plates 5, spacing sleeves 37 being disposed around said rod at opposite sides of said pedal.

The spring devices 25 normally lower the arms 23 so that the pressing roll 19 is normally lowered. Depression of the foot pedal 34 however, causes the connection 32 and the bar 29 to operate the levers 27 in such manner as to upwardly swing the arms 23, thereby raising the roll 19 to force the work against the work-performing roll 10. The bar 29 may incline slightly in one direction or the other to rock the levers 27 and swing the arms 23 to the proper extents according to varying thicknesses of the material being sand-papered or otherwise finished, and the construction and arrangement of parts is such that the pressing roll 19 may float ver-

tically to compensate for slight inaccuracies in the material, during which floating movement, the opposite ends of the roll need not move uniformly, due to the relative movement which the levers 27 and the arms 23 are permitted to have. All upward pressure of the roll 19 against the work is yieldable, due to the elastic connection 32.

While the general construction shown and described may be followed if desired, it is to be understood that within the scope of the invention as claimed, variations may be made.

I claim:—

15. 1. In a machine of the class described, a pressing roll, two vertically swingable arms having bearings supporting said roll, two levers separate from and operatively connected with said arms for upwardly swinging them, springs operatively connected with said arms for downwardly swinging them, a transverse bar operatively connected with said levers, a foot pedal under the center of said bar, and a vertical connection between said foot pedal and said center of said bar.
20. 2. In a machine of the class described, two parallel side plates having aligned openings, a pressing roll between said plates provided with trunnions passing loosely through said openings, horizontal arms having bearings for said trunnions, means at the rear ends of said arms pivoting them to said plates, horizontal levers fulcrumed between their ends to said plates in advance of said trunnions, the front ends of said arms being operatively connected with the rear ends of said levers, a transverse bar operatively connected with the front ends of said levers, springs acting on said arms for swinging them downwardly, a foot pedal below the center of said bar, and an elastic connection between said bar and pedal.
25. 3. A machine of the class described comprising two parallel vertical side plates formed with aligned openings spaced from their upper edges, a transverse work-performing roll extending between said side plates above said openings, a work-supporting table supported by said side plates immediately under said roll and having a slot extending longitudinally of the latter, a pressing roll whose upper portion is received in said slot, said pressing roll being provided with trunnions passing through the above-named openings, arms at the outer sides of said side plates having bearings for said trunnions, means at the rear ends of said arms pivoting them to said side plates, levers operatively connected with the front ends of said arms for upwardly swinging the latter, said levers being fulcrumed to said side plates, springs acting on said arms for normally swinging the same downwardly, a transverse bar operatively connected with

said levers, and depressing means for said bar embodying a foot pedal.

4. In a machine of the class described, a pressing roll, two vertically swingable arms having bearings supporting said roll, two levers separate from and operatively connected with said arms for upwardly swinging them, springs operatively connected with said arms for downwardly swinging them, a transverse bar operatively connected with said levers, a foot pedal under the center of said bar, and a vertical connection between said foot pedal and said center of said bar.

In testimony whereof I have hereunto affixed my signature.

PETER MARCHESINI.
